SHAPING DIE

Lewis E. Burger and Jennings B. Skinner, San Diego, Calif., assignors to Solar Aircraft Company, San Diego, Calif., a corporation of California

Original application February 23, 1944, Serial No. 523,516. Divided and this application March 31, 1945, Serial No. 585,842

3 Claims. (Cl. 113—49)

1

This invention relates to the die stamping art in which metal sheets are stretched and bent into desired shapes by pressing or striking them between dies, and more particularly to that phase of the art in which a plurality of sets of dies of successively greater depth are required to produce the desired shape.

This application is a division of our copending application Serial No. 523,516, filed February 23, 1944, and entitled "Method of making preliminary shaping die," which issued as Patent No. 2,383,706 on August 28, 1945.

An object is to provide preliminary dies of superior shape in that they so prepare the sheet metal for the final dies that the latter can produce deep and abrupt slopes without breaking or excessively thinning or wrinkling the metal.

Heretofore, when a stamping or drawing operation of more than one stage was necessary in order to produce a satisfactory deep or abrupt slope in a work sheet, it was the practice to have the dies used in the preliminary stages made manually by highly skilled pattern makers who produced them largely by the process of trial and error and with the expenditure of a great deal of time.

In accordance with the present invention, we provide a routine procedure for preparing preliminary dies from finish dies, greatly reducing the amount of time and skill required and yielding dies more uniformly satisfactory than those formerly made by highly skilled pattern makers.

The present invention is based on the principle that the preliminary drawing or stamping operations should so shape the sheet that the final operation is largely a bending operation, involving relatively little stretching or compression of the sheet. Hence, we make the preliminary dies with substantially the same absolute area as the final die but having less depth so that the projected area is greater. This result is obtained by using as a pattern for making the preliminary die a substantially non-stretchable, flexible sheet that has been first shaped in the finish die and then flattened out by bending to reduce its depth. A suitable material for such a sheet is wax reinforced by fabric in such a way as to prevent it from stretching or shrinking, while permitting it to bend.

A full understanding of the invention may be

2

had from the following detailed description with reference to the drawing of a specific procedure in accordance with the invention.

In the drawing:

Fig. 1 is a perspective view of a pattern for a finish die;

Fig. 2 is a cross section of the pattern of Fig. 1 taken in the plane II—II and showing a wax pattern sheet formed therein;

Fig. 3 is a perspective view of a pattern for a preliminary stage die made in accordance with the present invention from the finish pattern of Fig. 1;

Fig. 4 is a cross section of the wax pattern sheet as it appears when removed from the pattern of Fig. 2;

Fig. 5 is a cross section of the pattern sheet after it has been partially flattened out, the section being taken in the position corresponding to the line V—V of Fig. 3;

Fig. 6 is a cross section showing the pattern sheet of Fig. 5 supported and reinforced with plaster;

Fig. 7 is a cross section showing the reinforced pattern sheet of Fig. 6 inverted and mounted in a box ready for casting the plaster pattern of Fig. 3; and

Fig. 8 is an enlarged detail cross section of a portion of the pattern sheet.

Referring first to Figs. 1 and 2, there is shown a plaster pattern 10 for making a female finish die for use in a drop hammer or the like for shaping sheet metal. In accordance with well known procedure, the die may be cast in a sand mold, which mold was first formed from the pattern 10. Insofar as the present invention is concerned, either the pattern 10 or the finish die formed therefrom can be employed since both are of identical shape. It is usually most convenient to employ the plaster pattern 10.

It is to be understood that in the stamping press or drop hammer, a male die or punch is employed and that the sheet metal to be shaped is pressed or struck between the male and female dies. However, it is customary to make the male die or punch from the female die, and hence, it is sufficient in connection with the present invention to disclose the method of preparing the pattern for only the female die, the latter being hereinafter referred to as the "die."

There is shown in Fig. 3, a plaster pattern 11 for forming the preliminary die which is used to shape the sheet metal before it is placed in the finish die corresponding to the pattern 10 of Fig. 1. It will be observed that the pattern 11 of Fig. 3 bears little resemblance to the pattern 10 of Fig. 1, yet the shape of pattern 11 is inherently such as to prepare the sheet metal for stamping in the finish die so that it can take the form of the finish die without breaking and without thinning or wrinkling excessively. The reason for this is that the total surface of the pattern 11 is substantially the same as that of Fig. 1, the depth of pattern 11 being substantially less and the projected area correspondingly greater. Pattern 11 is obtained in accordance with the present invention by the following procedure:

First there is formed in the finish pattern 10 a thin pattern sheet 12 of wax reinforced with cheesecloth. This is done by first painting the surface of the plaster pattern 10 with a thin paint of modeling clay, liquid soap and water to prevent the pattern sheet 12 from sticking to the plaster. Before this paint has dried, a first sheet 13 (Fig. 8) of cheesecloth is placed on the pattern 10 and pressed into intimate contact with the surface thereof, the cheesecloth being sufficiently yieldable to permit such shaping.

Next, the cheesecloth 13 is coated with a suitable wax 14 by applying it on top of the cheesecloth 13 in melted condition with a brush. At the same time the cheesecloth is again forced into all the corners of the pattern with the brush. The wax congeals as soon as it is applied to the cheesecloth by virtue of conduction of heat therefrom into the plaster pattern, and by repeated applications of the molten wax with the brush, the layer 14 of wax is built up to a depth of approximately $\frac{3}{2}$ of an inch.

Next, a second sheet of cheesecloth 15 is pressed into the wax 14 while the latter is relatively soft, this second sheet 15 being laid on the bias with respect to sheet 13; that is, with its threads running at approximately 45° with respect to the threads of cloth 13. Thereafter, a final thin coat 16 of wax is brushed on to the cloth 15, thereby completing the pattern sheet 12 as shown in Fig. 2.

After it has cooled a little more and becomes fairly stiff, the pattern sheet 12 is removed from the pattern 10 by gradually pulling it away therefrom with the hands. It comes away quite readily because of the thin coat of modeling clay, liquid soap and water that was placed on the plaster pattern before the pattern sheet was formed. As removed from the pattern 10, the pattern sheet 12 appears as shown in Fig. 4, having the shape of the finish pattern 10. It is then flattened out into the shape shown in Fig. 5, this flattening operation being performed by pulling the pattern sheet apart with force applied at juxtaposed points on the edge thereof accompanied by slight force applied to the under side of the intermediate portion with the hands. This operation changes the shape of the pattern sheet without appreciably changing its area because the two sheets of cheesecloth laid on the bias with respect to each other largely prevent stretching of the pattern. Such stretching could not be avoided if the pattern sheet were made of wax alone without any fabric reinforcement.

After the pattern sheet has been flattened as shown in Fig. 5, it is used to cast the preliminary stage plaster pattern shown in Fig. 3 by the procedure illustrated in Figs. 6 and 7.

Referring to Fig. 6, the pattern 12 is first sup-

ported at relatively closely spaced points on its under surface by means of clay bolsters 17 extending upwardly from a supporting table or base 18, after which a thick layer 19 of plaster of Paris is applied to the upper surface of the pattern sheet, this layer 19 being formed by applying plaster in relatively stiff condition with a trowel, or with the hands.

After the plaster backing 19 has set, the assembly of the pattern sheet 12 and the backing 19 is removed from the clay bolsters 17, inverted and supported on clay bolsters 20 extending upwardly from a base 21 as shown in Fig. 7. Thereafter, side walls 22 of wood or other suitable material are constructed around the plaster backed pattern sheet to form therewith a mold into which liquid plaster of Paris can be poured. When this plaster of Paris has solidified and has been removed from the mold, it constitutes the preliminary pattern of Fig. 3.

It will be observed from the procedure described that the invention provides a routine process for developing patterns for preliminary dies from patterns of finish dies, requiring very little special skill. Furthermore, the procedure is relatively simple and does not require much time.

In some cases, it is necessary to employ more than one preliminary die to bring the sheet metal into the final desired form by successive stages, each involving a relatively small change in shape from the next preceding stage. Hence, in some instances, it may be desirable to form an intermediate stage pattern from the final pattern and then form a first stage pattern from the intermediate stage pattern. Under such conditions, the intermediate stage pattern can be prepared as described, after which a first stage pattern can be prepared from the same wax pattern by further flattening it and increasing its projected area and then using it to make the mold for casting the first stage pattern.

Although various waxes may be employed in forming the pattern sheet 12, a composition that has been found suitable in practice consists of a mixture of from one-half to two-thirds beeswax with the balance a pattern maker's wax such as "Master sheet wax" made by Kindt-Collins Co. of Cleveland, Ohio. If overheated, the wax may become too hard, under which condition it may be softened with the addition of a small amount of turpentine.

Various departures from the exact procedure described may be made, while still obtaining the advantages of the invention, and the latter is therefore limited only to the extent set forth in the appended claims.

We claim:

1. In the art of sheet stamping and drawing, a preliminary shaping die for partially forming and preparing sheets for further shaping with a second die having substantial curvature in all directions, said preliminary shaping die having a general configuration similar to the second die, and having substantially the same absolute surface area throughout as the second die, but having less depth and a correspondingly greater projected area than the second die.

2. In the art of sheet stamping and drawing, a preliminary shaping die for partially forming and preparing sheets for further shaping with a second die having substantial curvature in all planes intersecting the working surface of the die, said preliminary shaping die having the same general configuration as the second die, and having substantially the same absolute surface area

throughout as the second die, but having less depth and a correspondingly greater projected area than the second die, and having its steepest surfaces substantially less steep than the corresponding surfaces of the second die.

3. In the art of sheet stamping and drawing, a series of dies for successively shaping a work sheet in which all the dies have the same general configuration and are irregularly double curved and asymmetrical as to curvature and have the same absolute surface area, but in which one of the early stage dies has less depth and a correspondingly greater projected area than the next later stage die, and in which the steepest surfaces of said early stage die are substantially less steep than the corresponding surfaces of said later stage die.
